UNITED STATES PATENT OFFICE.

CAMPBELL P. HIGGINS, OF ROSELLE, NEW JERSEY.

DESIGN FOR A HEADER FOR SECTIONAL STEAM-GENERATORS.

SPECIFICATION forming part of Design No. 29,740, dated November 29, 1898.

Application filed October 27, 1898. Serial No. 694,752. Term of patent 14 years.

To all whom it may concern:

Be it known that I, CAMPBELL P. HIGGINS, a citizen of the United States, residing at Roselle, in the county of Union and State of New Jersey, have invented and produced a new and original Design for Headers for Sectional Steam-Generators, of which the following is a specification, reference being had to the accompanying drawings, forming part thereof.

Figure 1 is a front elevation of a header, showing my new design. Fig. 2 is a side view of the same.

As shown in the drawings, the leading or

material features of my design consist of the 15 serpentine contour of the header, (with the oval-shaped apertures on its face,) as shown in Fig. 1, and the inclined transverse depressions, with the zigzag back or rear side, which form a face of irregular vertical configuration. 20

Having described my invention, I claim as new—

The design for a header as herein shown, and described.

CAMPBELL P. HIGGINS.
